CLAIM

The ornamental design for an ultrasound simulator device, as shown and described.

DESCRIPTION

FIG. 1 is a perspective view of an ultrasound simulator device according to an embodiment of the present invention. FIG. 2 is a front view of the ultrasound simulator device of FIG. 1.

FIG. 3 is a rear view of the ultrasound simulator device of FIG. 1.

FIG. 4 is a left side view of the ultrasound simulator device of FIG. 1.

FIG. 5 is a right side view of the ultrasound simulator device of FIG. 1.

FIG. 6 is a top view of the ultrasound simulator device of FIG. 1; and,

FIG. 7 is a bottom view for the ultrasound simulator device of FIG. 1.

The dash-dot-dash broken lines represent the bounds of the claim, while all other broken lines are directed to environment and are for illustrative purposes only; the broken lines form no part of the claimed design.
